CLAIM

(57) The ornamental design for a Hanukkah gift box, as shown and described.

DESCRIPTION

FIG. 1 is a front elevational view of a Hanukkah gift box showing my new design;

FIG. 2 is a front perspective view thereof;

FIG. 3 is an alternate perspective view with the boxes shown in an open position; and,

FIG. 4 is an exploded perspective view with the boxes shown removed.

All surfaces not shown form no part of the claimed design.
